UNITED STATES PATENT OFFICE

STEPHEN D. HARTOG, OF BELLEVILLE, ILLINOIS, ASSIGNEE, BY MESNE ASSIGNMENTS,
TO THE CLEVELAND TRUST COMPANY, OF CLEVELAND, OHIO, A CORPORATION OF
OHIO

PISTON

Application filed January 11, 1928. Serial No. 611,959.

This invention relates to pistons.

An object of the invention is to provide an improved piston having a skirt and a head that are circumferentially disconnected and that are integrally united by ribs having their lower ends united to the skirt relatively a considerable distance below the top and having their upper ends united with the piston head portion and being intermediate disconnected from both parts of the piston.

Another object of the invention is to provide an improved piston embodying the structure mentioned and in which the head portion is designed and adapted to carry one or more piston rings.

Another object of the invention is to provide an improved piston embodying the structure first stated and in which the skirt of the piston is resiliently expandable when heated to form close contact all around with the cylinder wall.

Other objects will appear from the following description, reference being made to the drawings in which

Fig. 1 is a side elevation of my improved piston showing one of the slits in the skirt.

Fig. 2 is another side elevation showing one of the webs connecting the skirt with the head portion of the piston and designed and adapted for connection with a piston pin.

Fig. 3 is a vertical sectional view taken parallel with the axis of the piston pin bosses.

Fig. 4 is an inverted end view of the piston.

In the embodiment of the invention shown my improved piston is a casting comprising a head plate 1 having a depending annular portion 2 provided with a number of circumferential grooves 3 for the reception of piston rings; a skirt 4 separated from the head portion of the piston by a space 5 and integrally united with the head portion of the piston by webs 6. The webs 6 begin from a point above the lower end of the skirt about one-third of the length of the skirt and extend inwardly and upwardly and thence outwardly to integral union with the annular portion 2 of the head of the piston, having

up to integral merger with the head 1. Bosses 8 extending outwardly from the webs 6 in diametrically opposite alignment and are bored to receive a piston pin.

The skirt is provided with a pair of diametrically opposite slits 9 extending upwardly from the lower ends and terminating in enlarged openings 10 having an appropriate relationship to the piston pin bosses.

In the embodiment shown the openings 10 are slightly below the plane of the piston pin bores in the bosses, thus extending the slits slightly more than half of the vertical length of the skirt. This construction in which the webs 6 are wholly disconnected from the skirt of the piston, except at their lower ends, leaves the skirt freely expandable and contractible, thus providing a guide section for the piston that will maintain yielding contact with the cylinder walls for relatively a considerable portion of the length of the piston.

The openings in the side walls of the skirt opposite the webs 6 and the slits 9 provide oppositely formed upper and lower resiliently yieldable sectors so that the entire skirt of the piston is permitted to expand more properly under the influence of heat than it otherwise could expand. Moreover,

the webs 6 permit the head portion of the piston to expand quite extensively without appreciable effect upon the skirt guide section. This is because the form of the webs provides a pivotal point or fulcrum at a position slightly in advance of their intersection with the skirt or guide portion and permits the webs to yield resiliently under the influence of the greater heat to which the head of the piston is subjected.

These features of construction are highly important in the present invention and when embodied in a piston of the type disclosed obtain highly satisfactory results. These features avoid the binding of the piston in the cylinder which sometimes occurs in the case of pistons having transverse webs, as distinguished from the arcuate connecting webs 6.

I am aware that the construction may be varied within equivalent limits without departure from the nature and principle of the

invention and I do not restrict myself un-
essentially.

What I claim and desire to secure by Let-
ters Patent is:—

- 5 1. A piston, comprising a head, a skirt cir-
cumferentially separated from the head and
having two diametrically opposite openings
extending downwardly from its upper end
and having slots extending upwardly from
10 its lower end and terminating above the
plane of the lower ends of said openings and
below the upper end of the skirt, and in-
wardly projecting webs connecting the lower
portion of the skirt in the vertical planes of
15 the lower ends of said openings with said
head above said openings and adapted to sup-
port a piston pin.
2. A piston, comprising a head, a skirt cir-
cumferentially disconnected from the head
20 having diametrically opposite openings ex-
tending downwardly from its upper end hav-
ing slots extending upwardly from its lower
end and terminating at points below the
upper end of the skirt and above the plane
25 of the lower edges of said openings, and webs
forming integral connections between the
head and the skirt in line with said openings.
3. A piston, comprising a head, a skirt
30 circumferentially separate from the head and
having openings extending downwardly
from its upper end at diametrically oppo-
site sides and having slots between said open-
ings extending from the lower ends of the
skirt approximately one-half and less than
25 the entire length thereof, and webs having
their lower ends integrally united with said
skirt in the vertical planes of said openings
and having their upper ends integrally
united with said head.
- 40 4. A piston, comprising a head, a skirt cir-
cumferentially separate from the head and
having openings extending downwardly
from its upper end at diametrically opposite
sides, and having slots between said openings
45 extending from the lower ends of the skirt
approximately one half and less than the
entire length thereof and terminating above
the plane of the lower ends of said openings,
webs having their lower ends integrally
50 united with said skirt below said openings
and having their upper ends integrally united
with said head, and piston pin bosses sup-
ported by said webs and having their outer ends
substantially within the circumference of the
55 skirt.
5. A piston, comprising a head having a
number of circumferential grooves adapted
60 to receive piston rings, a skirt circumfer-
entially disconnected from the head and having
a split lower portion and having openings
extending downwardly from its upper end
to a plane below the upper end of said split
portion, and webs having their lower ends in-
65 tegraphically united with the skirt below said

openings and having their upper ends in-
tegrally united with said head.

6. A piston comprising a cup-like head
having a circumferential groove adapted to
receive a piston ring, a skirt circumferen-
70 tially disconnected from the head and hav-
ing a slit extending upwardly from its lower
end and having openings extending down-
wardly from its upper end at diametrically
opposite sides, webs integrally united with
75 said skirt below said openings and extending
upwardly and inwardly and having their up-
per ends extending outwardly and integrally
connected with the lower portion of said cup-
like head, and piston pin bosses integral with
80 said webs.

7. In a piston, a head, a skirt circumferen-
tially disconnected from the head and having
diametrically opposite openings extending
85 downwardly from the upper end, approxi-
mately U-shaped webs each having its lower
end integrally united with the piston below
one of said openings and its upper end in-
tegrally united with the head, and piston pin
90 bosses within the U of said webs and having
their outer ends within the circumference of
the skirt.

8. In a piston, a head, a skirt circumferen-
tially disconnected from the head and having
diametrically opposite openings extending
95 from the upper end downwardly more than
one half of the length of the skirt, and slits
extending upwardly from its lower end more
than one-half and less than the entire length
of the skirt, webs having their lower ends in-
100 tegraphically united with the piston below said
openings and their upper ends integrally
united with the head, and piston pin bosses
on the outer sides of said webs and having
their outer ends within the circumference of
105 the skirt.

STEPHEN D. HARTOG.
